011-4.

OR 012,261

Ex

UNITED STATES PATENT OFFICE.

LORENZ BISSINGER, OF PFORZHEIM, BADEN, GERMANY.

DESIGN FOR BRACELET.

SPECIFICATION forming part of Design No. 12,261, dated May 17, 1881.

Application filed November 23, 1880. Term of patent 7 years.

To all whom it may concern:

Be it known that I, LORENZ BISSINGER, of Pforzheim, in the Grand Duchy of Baden and Empire of Germany, have invented a new and original Design for Bracelets, of which the following is a full, clear, and exact description, reference being had to the accompanying photographic illustration, making part of this specification.

- 10 This invention has for its object a neat and attractive design for bracelets; and it consists in making the face thereof of raised studs or balls arranged in parallel lines, as hereinafter described.
- 15 The accompanying photographic illustration is a perspective view of a bracelet embodying the invention.
- a represents the body of the bracelet. The ornamental face or outer portion is composed
- 20 of projecting metal studs or balls b, arranged

in parallel circumferential rows, as shown, and constitutes an ornamental and pleasing design.

I am aware that in the jewelers' art it is common to arrange settings of different kinds in raised positions, and hence I make no broad claim to a bracelet provided with raised studs or gems; but

I claim—

A design for a bracelet, consisting in the combination, with the body of a bracelet, of a series of circumferential rows of raised metal studs or balls constituting the ornamental face, as shown and described.

In testimony that I claim the foregoing as my invention I have signed it this 11th day of November, 1880.

LORENZ BISSINGER.
